SHIP SALVAGING BARGE

Salvatore Basile, Bloomfield, Conn.

Application November 1, 1943, Serial No. 508,533

7 Claims. (Cl. 114—49)

My invention relates to the class of devices which are employed for raising sunken ships, and an object of my invention, among others, is to provide a device in the form of a barge by means of which sunken vessels may be raised in a most effectual manner and when raised may be conveyed to any suitable point for further operations.

One form of a ship salvaging barge embodying my invention and in the construction and use of which the objects herein set out, as well as others, may be obtained is illustrated in the accompanying drawings, in which—

Figure 1 is a view in side elevation, partially in section, of a salvaging barge embodying my invention on a plane denoted by the broken line 1—1 of Fig. 4.

Figure 2 is a view in cross section on a plane denoted by the broken line 2—2 of Fig. 4, looking toward the bow.

Figure 3 is a view in cross section on a plane denoted by the broken line 3—3 of Fig. 4, looking toward the stern.

Figure 4 is a top plan view of the barge with parts broken away to show construction.

Figure 5 is a perspective detail view on enlarged scale illustrating one of the lifting devices.

Figure 6 is a perspective view illustrating a fragment of the barge broken away and showing the use of the devices for supporting the ship being salvaged and to maintain it in an upright condition.

Figure 7 is an elevational view of a diving bell used in connection with the apparatus.

Figure 8 is a view of a fragment of the salvaging barge illustrating means for increasing its buoyancy.

As illustrated in the accompanying drawings my improved salvaging barge considered from a broad standpoint comprises two parts 10—11 pivotally attached together by a pivot 12 located at or near the stern and secured together at the opposite end by means of a series of hooks 13 secured to a vertically mounted shaft 14 preferably extending from the deck downwardly to the bottom of the barge and operated to secure the two barge sections together and to release them by means of a piston in a cylinder 15 connected with said shaft by an arm 16 secured to the upper end of the shaft. The two barge sections are securely fastened against independent vertical movement by means of wedge-shaped projections 17 on one section entering notches of like shape on the opposite section, as shown

in Fig. 2 of the drawings. The same construction is arranged at the rear end of the barge where wedge-shaped projections 18 located forward of the pivot 12 interengage and are held so engaged by hooks 19 secured to a shaft 20 pivotally mounted vertically and connected by an arm 21 with a piston in a cylinder 22, the pistons being operated in any suitable manner, a description of which is not necessary herein.

- 10 In order to accommodate a vessel being salvaged the half members of the barge are recessed on their inner or confronting sides, these recesses 23—24 constituting a well shaped to conform generally to the shape of the ship being salvaged and wherein said ship may be suspended for repairs or transport. A Diesel engine 25 in the stern of each half of the barge is connected with a propeller 26 for the purpose of driving the barge. Cylinders 27 with opposed pistons therein pivotally connected with ears 28 at the rear end of the recesses 23—24 are employed to open and close the barge halves, these cylinders being supplied with any suitable pressure fluid in any ordinary manner which will be readily understood by those skilled in the art. To limit the outward swinging movement of the barge halves cables (not herein shown) extending across the well constituted by the recesses 23—24 and which may be removed as the ship is gradually enclosed within the well are employed. Closing of the barge halves may be facilitated by means of winches (not specifically shown) to receive the limitation cables to assist the cylinders 27 in the closing operation of the barge halves.

When a ship being salvaged has been enclosed within the well between the barge halves, as hereinbefore explained, it is held in a vertical position (or on an even keel if listing) by sets 40 of pistons 29—30 operating in cylinders 31—32 with devices on the ends thereof which are engaged with the sides of the ship being operated upon. Each piston 29 carries a hinge contact member 33 while each piston 30 carries a roller 34 at its outer end for contact with the sides of the ship 35 being operated upon.

To raise or support a sunken ship a number of gripping devices 36 are located in recesses 37 formed in opposite walls of the well formed 50 between the barge halves and along the length thereof. Each of these gripping devices consists of a pair of supporting side members 38 (see Fig. 5) having cables 39 attached to their upper ends and passing over sheaves 40 on a hoisting frame 41 rising from the deck in prox-

imity to a recess 37, said cables passing downwardly to a winch 42 on the deck of the barge. Each of these gripping devices comprises arms 43-44 pivotally attached at their inner ends to the side parts 38. Each arm 43 is operated by means of a piston rod 45 extending into a cylinder 46 which cylinder may be supplied with any suitable pressure fluid in any desired manner and not essential to be shown herein, as this will be well understood by anyone skilled in the art. The arms 43 are directly pivotally attached to a carrier bracket 49 slidably mounted between the sides 38 and which is raised and lowered by means of a piston 50 extending into a cylinder 51 pivotally suspended between the sides 38 and which may be supplied with driving fluid in any suitable manner as hereinbefore explained. The outer ends of the arms 43 are formed to tightly grip the upper portion or deck of a ship being salvaged.

Each of the arms 44 as before stated is pivotally attached between the sides 38 of a lifting device and is raised or lowered by means of links 52 pivotally attached at one end to the arm and at its opposite end to a piston rod 47 operating in a cylinder 48. Each of the arms comprises a rest 53 at its outer end adapted to be engaged underneath with the bottom of the ship being salvaged, these rests being adjustable longitudinally within the arm by means of a piston rod 54 in a cylinder 55, this cylinder as well as the others hereinbefore referred to, being supplied with a driving fluid in any suitable manner and as may be desired. It will thus be seen that the arms 43 and 44 with their contacting members may be readily adjusted to suit the size of the ship being salvaged and to properly engage said ship to firmly hold it while being raised.

Braces 57 are pivotally attached at one end to the arms 44 and at their opposite ends to the sides 38 as a supplemental means for supporting the arms when actuated to lift a load. The upper ends of the links 52 are attached to the sides 38 by means of pivots 58 vertically movable in slots 59 in said side parts.

A pointed member 56 is affixed at the lower ends of each of the hoisting or lifting devices 36 to more easily enter the sea bottom and thereby firmly steady the lifting devices while a ship is being raised.

To supplement the barge's weight sustaining ability, as when raising a large heavily laden ship, pontoons 60 suspended from davits 61 mounted on the deck of the barge are employed to be positioned on the water surface and fastened by cables 62 of an endless type controlled by winches 63 mounted on the deck of the salvaging barge, a showing of these winches appearing in Figs. 2 and 3.

The pontoons may also serve a useful purpose as rafts onto which freight from the ship being salvaged may be transferred, thereby relieving the strain from the lifting mechanism. Cork fill 64 within the barge walls (see Fig. 8) may be used to increase the buoyancy of the barge, and built-in pontoons 65 may be employed for the same purpose.

These pontoons 65 are in fact air tight compartments and comprise an important feature of my invention. There are many of them constituting enclosed chambers that are preferably arranged in a row and touching each other as shown in Fig. 8. They are each gradually tapered from a narrow dimension at the bottom increasing in width toward the top, the bottom

edges being preferably located at or just below the normal water line of the barge. This construction provides a series of water-tight compartments positioned preferably outside of the barge along the top, thereby increasing buoyancy of the barge as it is lowered in the water either from sustaining load or from injury or other causes. It will be observed that this construction may be applied to vessels in general and not limited necessarily to salvaging barges.

Pockets 66 for diving bells 67 are formed in the deck of the barge and which bells may be raised and lowered as by means of cables operating from davit frames 68, as shown in Figs. 3 and 4 of the drawings. These diving bells are supplied with telephone, two-way radio, camera, and other communication means as well as necessary control means for operation of the attached cables 69 for moving the diving bells from place to place and for following the operator's telephone instructions to cable men on the deck of the barge. The diving bells will also be provided with such other instruments of various kinds including oxygen tanks and other paraphernalia as may be required. Each bell will be constructed with a section thereof fitted with flexiglass or other suitable transparent material to give the operators within the bell full scope of vision.

30 An entrance hatch 76 is provided in the top of the bell for access thereto. A loud speaker 77 and a two-way radio 78 are also shown as equipment for the bell. A system 79 of levers for outside communication is also provided, as herein shown these comprising three levers for this purpose. Operation of the lever to the left for instance indicating a desire for movement of the bell on the left, that on the right a desire for movement of the bell to the right, and the center lever if moved up denoting a desire for the bell to be raised, and a downward movement of said lever denoting a direction for lowering the bell.

It will be noted that as shown in Figs. 2 and 4 a carriage 80 that supports the sheaves 40 may 45 be moved laterally of the barge to move the gripping devices 36 forward or back toward and away from the vessel being operated upon.

A combination deck house 70 for navigation purposes and operation of the salvaging equipment of the barge is located near the aft end thereof. This gives a centralized position from which to direct various maneuvers in connection with securing a ship to be salvaged. This deck house is so constructed that when the barge 55 halves are opened a set of rollers 71 in the bottom of the overhanging section will permit ease of movement to permit the barge sections to be operated, as shown in Fig. 3. Air compressors 72 with ample tank equipment 73 are provided for 60 operation of the mechanisms hereinbefore described for securing a sunken ship in the barge well, and to supply with air as needed the pontoons or other air operated devices.

Auxiliary Diesel engines 74 for driving generators to furnish current for the motors on winches and for lighting and other purposes are located in the barge halves, and motor driven pumps 75 are stationed on the deck of the barge halves to remove water from the salvaged ship after getting it to the surface and for such repairs as may be needed.

70 Stairways are located in numerous places to connect the several decks in the barge halves and removable rails are furnished about the outside

edges of the upper deck where required, such parts not requiring a specific showing herein.

I claim:

1. In combination in a salvaging barge having a well substantially at the center thereof of a capacity to receive a ship to be salvaged, a number of lifting devices located on opposite sides of said well, each of said devices comprising a supporting side member, an arm pivotally mounted on said supporting member, means for swinging said arm to engage the top of said ship, a bottom arm mounted on said device underneath said swinging arm, means for operating said bottom arm to engage underneath said ship, and means for raising said lifting device.

2. In combination in a salvaging barge having a well substantially in the center thereof of a capacity to receive a ship to be salvaged, recesses formed in the opposite walls of said well to receive lifting devices, lifting devices located in said recesses, each of said devices comprising a supporting side member, an arm pivotally mounted on said supporting member, means for swinging said arm to engage the top of said ship, a bottom arm mounted on said device underneath said swinging arm, and means for raising said lifting device.

3. In combination in a salvaging barge having a well substantially in the center thereof of a capacity to receive a ship to be salvaged, a number of lifting devices located on opposite sides of said well, each of said devices comprising a supporting side member, a carrier bracket mounted on said supporting member and vertically adjustable thereon, an arm pivotally attached to said bracket for engagement with the top of said ship, means for swinging said arm to engage the top of said ship, a bottom arm mounted on said device underneath said swinging arm, means for operating said bottom arm to engage underneath said ship, and means for raising said lifting device.

4. In combination in a salvaging barge having a well substantially in the center thereof of a capacity to receive a ship to be salvaged, a number of lifting devices located on opposite sides of said well, each of said devices comprising a supporting side member, an arm pivotally mounted on said supporting member to engage the top of said ship to be salvaged, means for swinging said arm to engage the top of said ship, an arm pivotally attached to said device underneath said swinging arm, means for swinging said bottom arm on its pivot on said supporting side member to position it relatively to the bottom of said ship,

means for engaging said bottom arm with the bottom of said ship, and means for raising said lifting device.

5. In combination in a salvaging barge having a well substantially in the center thereof with a capacity to receive a ship to be salvaged, a number of lifting devices located on opposite sides of said well, each of said devices comprising a supporting side member, a bracket vertically adjustable on said supporting member, means for imparting vertical movement to said bracket, an arm pivotally mounted on said bracket to engage the top of said ship, means for swinging said arm on its pivot, a bottom arm supported on and extending from said device underneath said swinging arm to engage the bottom of said ship, means for engaging said bottom arm with the bottom of said ship, and means for raising said lifting device.

6. In combination in a salvaging barge having a well substantially in the center thereof of a capacity to receive a ship to be salvaged, a number of lifting devices located on opposite sides of said well, each of said devices comprising a supporting side member, an arm pivotally carried by said supporting side member to engage the top of said ship, means for operating said arm, a bottom arm pivotally supported by said supporting member and extending outwardly therefrom, a rest movable longitudinally along said bottom arm to engage the bottom of said ship, means for extending said rest underneath the bottom of said ship, and means for raising said lifting device.

7. In combination in a salvaging barge having a well substantially in the center thereof of a capacity to receive a ship to be salvaged, a number of lifting devices located on opposite sides of said well, each of said devices comprising a supporting side member, an arm pivotally carried by said supporting member to engage the top of said ship, means for operating said arm, a bottom arm pivotally attached to said supporting member, a link pivotally attached to said bottom arm, a piston secured to said link, means at the top of said supporting member for operating said link to raise and lower said bottom arm, a rest movably supported lengthwise of said bottom arm, a cylinder mounted on said bottom arm, a piston operating in said cylinder and connected with said rest to extend the latter to engage underneath the bottom of said ship, and means for raising said lifting device.
